UNITED STATES PATENT OFFICE.

GLENN MORE, OF JAMESTOWN, NEW YORK, ASSIGNOR TO BLACKSTONE MANUFACTURING COMPANY, OF JAMESTOWN, NEW YORK, A CORPORATION OF NEW YORK.

GEARING FOR WASHING-MACHINES.

1,336,086.

Specification of Letters Patent.

Patented Apr. 6, 1920.

Application filed March 17, 1919. Serial No. 283,022.

To all whom it may concern:

Be it known that I, GLENN MORE, a citizen of the United States, and a resident of Jamestown, in the county of Chautauqua and State of New York, have invented certain new and useful Improvements in Gearing for Washing-Machines; and I do hereby declare that the following is a full, clear, and exact description thereof, reference being had to the accompanying drawings, and to the letters of reference marked thereon, which form a part of this specification.

This invention relates to improvements in power driven washing machines.

One of the objects of the invention is to provide an arrangement whereby the washing machine may be converted from a rotary, reciprocating or dolly type of machine into a vertical reciprocating or vacuum dasher type of machine, by interchangeable parts;—removing the operative parts of the rotary reciprocating type which connect the horizontal drive shaft on the top of the machine with the operating shaft mounted in the hinged lid of the machine, and substituting therefor the appropriate parts of the vertical reciprocating type of machine.

Another object of the invention is to provide a novel and convenient mechanism for coupling at will, the reciprocating shaft mechanism of either type of machine with the continuously rotating, horizontal driving shaft.

These and other objects of the invention will more fully appear as I proceed with my specification.

In the drawings:

Figure 1 is a plan view of a washing machine mechanism embodying my invention. Fig. 2 is a transverse, vertical sectional view of a portion of the tub and the lid, the latter and some of the parts carried thereby being indicated in dotted lines in a raised position, and other parts being in side elevation.

Fig. 3 is a vertical, sectional view, enlarged, taken upon the line 3—3 of Fig. 1, looking in the direction indicated by the arrows.

Fig. 4 is an end view of a standard, with one of the removable arms positioned thereon, the dotted lines indicating a change of position.

Fig. 5 is a side elevation, enlarged, and partly in section, of the horizontal drive

shaft, taken upon the dotted line 5—5 of Fig. 6.

Fig. 6 is a side elevation of a part of the horizontal drive shaft and the casting in which it is mounted, part being in section. 60

Fig. 7 is a cross sectional view of the horizontal drive shaft taken upon the plane indicated by the dotted line 7—7 of Fig. 6, looking in the direction indicated by the arrows. 65

Fig. 8 is a sectional view, enlarged, of a portion of the tub and the hinged lid, showing in side elevation the operating removable part for the vertical reciprocating type of machine. 70

Fig. 9 is a plan view of the parts shown in Fig. 8 the gears being in horizontal section.

Referring to that form of the invention embodied in Figs. 1, 2 and 3 of the drawings, A represents a suitable support which in this instance may be the round tub of a washing machine; B a movable top lid therefor; O the operating shaft, and S the driving shaft. The operating shaft O is 75 mounted so as to project vertically through a proper bearing 1 in the lid B of the machine, and to project into the tub A so that at its lower end there may be secured thereto a suitable washing machine tool, such, for example, as the familiar dolly or agitator D. This consists of a horizontally arranged disk provided with a plurality of downwardly and outwardly projecting blunt fingers d. The shaft bearing 1 projects upwardly from the plate 2 which may be secured by bolts 3 or otherwise to the lid B. A pinion 4 is secured to the upper end of the operating shaft O by a nut and bolt or other convenient means. A rocking segment 5, carrying a plurality of gear teeth 6 on its upper inner arc, adapted to mesh with the teeth of the pinion 4, is pivotally mounted upon a rock shaft 7, the latter having suitable bearings in the boss 8 of the bearing 1, and in the boss 9 integral with the plate 2. It is, of course, immaterial whether the segment 5 is secured to the rock shaft 7, so that the latter will rock in its journal bearing, or whether the shaft 7 is 80 fixed in its bearings and the segment 5 is supported upon and rocks about said shaft 7. 85

On the outer end of the driving shaft S is a crank arm 10 provided with a wrist pin 11. L is a link, one end of which is mounted 90

100

105

upon the wrist pin 11 and the other end is mounted upon a stud 12 projecting outwardly from and secured to the segment 5. It follows that as the shaft S is rotated continuously in one direction, the crank will cause the wrist pin end of the link L to rotate about the shaft and the link will thus actuate the segment 5 by a rocking motion about the shaft 7. As this segment 5 travels back and forth in its rocking movement, the teeth 6 will cause the pinion 4 and the shaft O to rotate alternately in opposite directions. Thus a continuous, rotary movement of the horizontal shaft S is translated into an alternating, rotary movement of the operating shaft O.

Motion may be communicated to the drive shaft S by any suitable means, as, for example, by means of the bevel pinion 13 mounted upon said driving shaft S and being engaged with a bevel pinion 14 mounted upon a stub shaft 15, said bevel pinion 14 being suitably geared at 16, or otherwise, to a pulley 17 about which may be placed a driving belt 18, driven from any suitable source of power.

Inasmuch as it is desirable to have the driving shaft S in motion when power is being applied, and at the same time have the operating shaft O under the control of the operator, so that it may be driven or not, as occasion requires, I have devised a mechanism which I will now proceed to describe:

The shaft S is suitably mounted in bearings h raised up from a plate or casting H, which latter may be secured to the support A by bolts 19 or other suitable means. The crank arm 10 is loosely mounted upon the outer end of the driving shaft S and on its inner end or face, said crank arm 10 is provided with a clutch member 20, having projecting engaging clutch lugs 21. Intermediate the clutch member 20 and the bearing h, and mounted upon the drive shaft S, is a sleeve or spool member 22 provided on its outer face with complementary clutch engaging lugs 23, and on its outer surfaces with a circumferential groove 24. The said sleeve or spool member 22 is secured to the shaft S by a spline 25 or other suitable means whereby motion of rotation of the shaft S will be communicated to the sleeve 22, and whereby said sleeve 22 may be shifted longitudinally of the shaft so that its complementary clutch lugs 23 may be engaged or disengaged with the lugs 21 of the clutch member 20. In order to move the sleeve 22 lengthwise of the shaft S, a bell crank lever 26 pivoted at 27 in the frame or housing H is provided with a lug or projecting arm 27' adapted to enter the circumferential groove 24. It is manifest that when the lever 26 is actuated, the arm or lug 27' will in turn actuate the sleeve 22 to slide it back or forth, as desired, upon the shaft S. It is further manifest that

when the clutch surfaces 21, 23, are disengaged, as shown in Figs. 1 and 9, no motion of rotation of the shaft S will be communicated through the crank 10 and link L to the operating shaft; and that on the contrary, when the clutch surfaces 21, 23, are in operative engagement, the clutch member 20 and the crank arm 10 will be locked to the shaft S and motion of rotation of the shaft S will be promptly communicated through the link L and associated parts, to the operating shaft O.

The operating shaft O and associated parts are, as I have stated, secured to the lid B, and it is desirable at times to raise the lid B, as shown, by dotted lines of Fig. 2. In order to form a suitable hinge, whereby the raising of this lid and desired parts may be thus accomplished, I have provided the following ingenious arrangement: I extend the casting 2 rearwardly and provide it with an upwardly and outwardly turned yoke Y comprising two arms 28, 29. Raised up from the plate or casting H, is a vertical support or standard 30, provided with an inwardly directed bearing stud 31, the longitudinal axis of which is in prolongation of and in the same horizontal plane as the longitudinal central axis of the shaft D. A suitable aperture is made in the end of the yoke arm 28, so that when in proper position, this arm 28 will fit over and rock upon the stud 31. The support or standard 30 is provided with a suitable stop shoulder 32 and the yoke arm 28 is provided with a complementary shoulder 33. When the arm 28 is raised to the predetermined position about the stud 31, the shoulder 33 engages the stop shoulder 32 and prevents further movement in the raised direction, all of which is clearly indicated in Fig. 4.

Fig. 5 illustrates the connection of the other yoke arm 29 with the driving shaft S. On the inner face of the arm 29 is an annular groove or depression indicated by the dotted line 34 in Fig. 5, of such diameter as to include or to nicely fit over the projecting end 35 of the shaft bearing h of the casting H. A slot opening 36 projects from one margin of the yoke arm end 29 and affords a proper bearing at its inner end for the shaft S. Thus the yoke arm 29 may be placed in juxtaposition upon the shaft S.

Projecting upwardly from the plate or housing H is a rib 37, of a thickness equal to that of the slot 36. This rib 37 is so positioned with reference to the end of the bearing hub h as to interfere with the proper positioning of the yoke arm 29 upon the driving shaft S excepting only when the slot 36 is directly opposite the margin or edge of the rib 37. In this position, the side walls of the slot 36 will straddle the side walls of the rib 37, and the inner end of the slot will be seated upon the shaft S. Thus

the entire yoke Y including the arms 28 and 29 may be bodily moved in a lateral direction, lengthwise of the shaft S; that is to say, the arm 29 is slid along upon the shaft 5 S until its circular recess 34 will engage and be supported on the end 35 of the bearing h, the arm 28 being at the same time moved in the direction of the standard 30 until the aperture in the arm 28 engages and is 10 mounted upon the stud 31. At this time the walls of the slot 36 of the arm 29 are free and disengaged from the rib 37. It will, thus, be manifest that the yoke Y and the lid B to which it is secured, may be raised 15 bodily upwardly, as upon a hinge, the stud 31 and the shaft S acting in the sense of hinge pins for the yoke Y.

In order to insure this free hinge movement of the yoke Y, it is necessary that it be 20 locked against such longitudinal movement as would disengage the yoke arm 28 from the stud 31, and the arm 29 from the bearing h, and as would cause the walls of the slot 36 of the yoke arm 29 to come in contact with and engage the rib 37. For this 25 purpose, I provide the bolt 38 projecting through the rib 37 and the lock nut 39 to project into the path of the yoke arm 29, thus preventing any longitudinal movement 30 of said yoke arms 28 and 29, while at the same time permitting the desired swinging or hinge movement. In order to remove the yoke arm 29 from the shaft S as well as the yoke arm 28 from the stud 31, it will first be 35 necessary to remove the bolt 38 from the rib 37, swing the yoke into such position as will cause the side walls of the slot 36 to register with the rib 37, then slide the yoke Y bodily toward the rib 37 until the recess 34 therein 40 is entirely clear of the shaft bearing end 35, when the yoke Y may be bodily lifted. The reverse procedure is, of course, necessary when applying the yoke Y.

It is desirable to convert the dolly type of 45 washing machine into the dasher type, and in Figs. 8 and 9, I have illustrated the means whereby this may be accomplished. In the modified forms thus shown in Figs. 8 and 9, the shaft S is provided with the crank 10 and the sliding clutch member 22, as heretofore explained, and the washing machine lid B is provided with the vertical operating shaft O, as before. On the lower end of this shaft O is mounted any suitable form of 50 churn or dasher or vacuum clothes washing device, indicated by the letter V, instead of the dolly type of device shown in the other figures. A plate or casting 40 may be bolted or otherwise secured at 41 to the lid B, and 55 it carries any suitable means of supporting the shaft O, so as to provide for vertical reciprocation of such shaft O, through the lid B. The said plate 40 is also provided with raised up, side wall standards 42, terminat- 60 ing in rock shaft bearings 43 for the rock

shaft 44. Suitable yoke arms 28, 29, project from the standards 42. The yoke arm 28 is adapted to fit over the stud 31 and the arm 29 is provided with a slot 36 to fit over the shaft S as heretofore explained. A rocking 70 sleeve or member 45 fits over the rock shaft 44 and is provided with two arms 46, 47, projecting from its opposite sides. The arm 46 is bifurcated so that its two ends 48, 48 straddle and are pivotally bolted to the upper end of the shaft O. The end of the arm 47 carries a suitable wrist pin 49, whereby said arm 47 is pivotally secured to one end of the link L. The other end of the link is mounted on the wrist pin 11 of the crank 80 arm 10.

It will thus be understood that continuous motion of rotation of the drive shaft S, when the clutch members 23, 21 are in locked engagement, will cause the wrist pin of the 85 crank 10 to rotate about the shaft S, and the connecting link L will cause the arm 47 to move up and down. As this arm 47 moves up and down, the sleeve 45 will necessarily rock about the shaft 44 and thus an up and 90 down, or rocking motion will be imparted to the outer end of the arm 46 and the continuous motion of rotation of the drive shaft will thus be translated into a reciprocating vertical motion of the operating shaft O. 95 The lid B may be swung up into a raised position by the two yoke arms 28, 29, acting as hinges, over the stud 31, and the shaft S, as in the former case.

This interchangeable form of casting is 100 very desirable in practice. The housewife has only to unbolt the plate 40 and disengage the ends 48 from the shaft O and substitute for the casting shown in Figs. 8 and 9, the casting shown in Figs. 1 and 2, changing, of course, the dasher V for the dolly, or vice versa, in order to convert the washing machine from a dasher type to a dolly type, or vice versa.

In making this change, the same means 110 for connecting up the driving shaft is used, and the same hinge connections of the yoke arms 28, 29. These parts are exceedingly simple, strong and durable. The operator learns readily that it is necessary only to 115 remove the bolt 38 and restore the bolt after the interchanged parts have been placed in position, to make this change.

I claim as my invention:

1. A fixed support, a frame secured 120 thereto, bearings on the frame, a driving shaft mounted horizontally in said bearings, a standard on the frame, a stud on said standard, combined with a second support, an operating shaft, a frame carrying 125 the operating shaft secured to said second support, means hingedly connecting the latter frame with said stud and the driving shaft, whereby the second support may be movably swung about the longitudinal axis 130

of the driving shaft as a center, and removable means on the operating shaft frame maintaining said connecting means in hinged operative relation.

5 2. A fixed support, a frame secured thereto, bearings on the frame, a driving shaft mounted horizontally in said bearings, a standard on the frame, a stud on said standard, combined with a second support, an operating shaft, a frame carrying the operating shaft secured to said second support, means hingedly connecting the latter frame with said stud and the driving shaft, whereby the second support may be 10 movably swung about the longitudinal axis of the driving shaft as a center, and removable means on the operating shaft frame maintaining said connecting means in hinged operative relation, said removable means including a bolt on the frame.

3. A fixed support, a frame secured thereto, bearings on the frame, a driving shaft mounted horizontally in said bearings, a standard on the frame, a stud on said standard, combined with a second support, an operating shaft, a frame carrying the operating shaft secured to said second support, means hingedly connecting the latter frame with said stud and the driving shaft, whereby the second support may be 25 movably swung about the longitudinal axis of the driving shaft as a center, and removable means on the operating shaft frame maintaining said connecting means in hinged operative relation, said removable

means including a bolt on the frame below the driving shaft, located transversely thereof and in the path of said hinged connecting means when the latter is moved bodily, longitudinally of the driving shaft. 40

4. A fixed support, a frame secured thereto, shaft bearings in said frame, one of which is provided with a circumferential bearing boss projecting from the frame, a driving shaft rotatively mounted on said frame, a crank on one end of said shaft, a standard on said frame located near the crank end, a pivotal stud on said standard in axial alinement with the driving shaft, a second support, a frame secured thereto, 45 and provided with two arms, one of which arms is provided with an aperture adapted to engage said stud and the other with a circular recess adapted to fit over said projecting bearing boss, one of the arms being 50 also provided with a slot of a width at least equal to the diameter of the driving shaft, and a rib on the first mentioned frame located adjacent to but not in alinement with the bearing boss, the rib being of the 55 thickness equal to the width of the slot.

In testimony that I, GLENN MORE, claim the foregoing as my invention I affix my signature in the presence of two witnesses, this 12th day of March A. D. 1919.

GLENN MORE.

Witnesses:
